UNITED STATES PATENT OFFICE.

CHRISTIAN N. ILENG, OF CHICAGO, ILLINOIS.

CAR WINDOW SASH.

Application filed April 18, 1918. Serial No. 229,461.

To all whom it may concern:

Be it known that I, CHRISTIAN N. ILENG, a citizen of the United States of America, and resident of Chicago, Illinois, have invented a certain new and useful Improvement in Car Window Sashes, of which the following is a specification.

This invention contemplates a novel and practical method of salvaging old car window sashes for the purpose of building new sashes from the unimpaired, usable sections thereof. Ordinarily, car window sashes, which are made of metal, are thrown away when they become rusted or broken. Prior to this invention, so far as now known, there was no practical method which could be employed for the purpose of building new sashes from the unimpaired or usable sections of the old sashes. Consequently, as stated, the old sashes, including the locks, were ordinarily discarded, and while they were, of course, capable of being melted up for old metal, such as brass, they were regarded as being without value for the purpose of building new sashes. In accordance with this invention, therefore, the old sashes are employed in the manufacture of new sashes, by separating the rusted or otherwise impaired portions from the usable sections, and by splicing together the usable sections to form new sashes. In this way, on an average, two or three old sashes can be salvaged to produce a new or reconstructed sash. But it will be understood that the number of new sashes to be produced from any given number of old sashes will depend upon the condition of the latter.

To this and other useful ends the invention consists in matters hereinafter set forth and claimed and shown in the accompanying drawings, in which—

Figure 1 is a front elevation of the car window sash produced or reconstructed from old and worn out or rusted sashes, embodying the principles of the invention.

Figure 2 is an enlarged horizontal section on line 2—2 in Figure 1.

Figure 3 is a perspective of one of the splicers shown in dotted lines in Figure 1.

Figure 4 is an enlarged vertical section of one of the lower corner portions of the sash.

Figure 5 is a horizontal section on line 5—5 of Figure 4.

Figure 6 is a front elevation of the corner portion shown in Figure 4.

Figure 7 is an enlarged rear elevation of one of the locks shown in previous views.

Figure 8 is a detail view showing the invention applied to a different form of sash. 60

Figure 9 is a section on line 9—9 of Figure 8.

As thus illustrated the invention comprises a rectangular car window sash composed of hollow metal sections 1, 2, and 3, 65 forming the upper portion of the frame, and other sections 4, 5, 6, 7, and 8 forming the lower portion of the rectangular sash or frame. These sections are formed by cutting the old sashes into lengths and in many 70 cases the entire top of a sash and half the sides thereof can be saved. For example, as shown, the sections 1, 2, and 3 can be the unimpaired upper portion of an old sash, as the rusting occurs in the lower portion of 75 the sash to a greater extent than in the upper portion, so that while the lower portion of the sash may be badly rusted in some cases, the upper portion will be practically as good as new. The lower portions 4, 5, 6, 80 7, and 8, can be cut from other old sashes, from the upper portions thereof, it being understood that the method contemplates the saving of any and all portions of the sashes which are usable, and this will involve the use of the salvaged or saved sections in different lengths. In this way butt-joints are formed at 9, 10, 11, and 12, by the insertion of splicers within the ends of the hollow sections, and for the forming of the 90 sash, shown in Figures 1 to 7 inclusive, the splicer shown in Figure 3 may be employed. This splicer comprises a pair of channel bars 13 spaced apart and connected by rivets or short rods 14, the splicers being formed to 95 fit the interior of the brass or other sheet metal sections of the sash (see Figure 2), so that the usual or ordinary groove 15, for the edge of the glass, will extend into the splicers. These splicers can be secured in 100 place in any suitable or desired manner, but are preferably incorporated by sweating or by braising or some other method of soldering; but when sweated in they are practically integrally united to the hollow sections of the sash, and each joint is smoothed and finished in a way that makes it practically unnoticeable, but at the same time very strong, and in this way the reconstructed sashes not only have miter-joints 110 at the corners, but also one or more butt-joints at random between the corners. As

shown in Figure 1 the upper corner splicers 16 can be those that are ordinarily employed, and which form the miter joints for the corners inasmuch as the upper corners of the old sashes are usually in good condition and do not need reconstruction. However, the lower corner splicers 17 must be specially treated and are of a particular character, inasmuch as in the old sashes 5 they were associated in a particular manner with the locks which are ordinarily found at the lower corners of a car window sash and are usually badly rusted. Each of the lower splicers 17 is, therefore, preferably of the form shown more clearly in Figure 4, and are applied as follows:

The old splicer 17 is reinforced and somewhat enlarged by a bent strip of metal 18, preferably of brass, held in place by rivets 10 19 inserted through the splicer. The ends of the sections 4 and 6 are bevelled to form a miter joint and the ends of the sections 5 and 8 are also bevelled to form a miter joint, and the reinforced splicers 17 are 15 then inserted in place. Slots 20 and 21 are formed in the sash, adjacent each lower corner, and holes 22 and 23 are formed in the sash opposite the holes 24 and 25 in the splicer. The old locks are removed from 20 the old sashes and the backs of the locks are changed so that they have the appearance of the lock shown in Figure 7, the back plate of each lock 26 being bevelled along its edges 27 and 28 and being formed 25 with lugs 29 and 30 to enter the slots 20 and 21, whereby these lugs 29 and 30 extend inside of the sash and are thus concealed. The openings 31 and 32 of said lugs will come opposite the holes 22 and 23 30 and also opposite the holes 24 and 25, and when screws are inserted in these holes or openings the locks will not only be secured in place, but the corner sections of the sash will also be held tightly together. In this 35 way a new sash is made from the old sashes, and a method of salvaging the old sashes is provided which results in a considerable saving, as the new sashes which are thus built from the old sashes can be used in 40 the cars from which the old sashes were taken, or in new cars, if desired, so that the old sashes are not a total loss and are employed in a way that makes them more valuable than they would be for merely 45 scrap metal purposes.

As shown in Figures 8 and 9, the sash is of a somewhat different shape, and does not have the groove 15 previously described.

In this case the splicer 33 is a piece of bent sheet metal which fits the interior of the sections of the sash, but it may be sweat-ed or braised or soldered in place in any suitable or desired manner, and the effect is the same as in the previous construction, inasmuch as a strong and smooth joint is 65 produced which is practically not noticeable.

From the foregoing it will be seen, therefore, that portions of the old sashes which have heretofore been thrown away or merely melted up again are employed in 70 the building of new sashes, and that even the locks of the old sashes may be saved by this method of salvaging the old sashes, and that new sashes are built which very closely resemble the old sashes and which 75 are well adapted for use in the car windows from which they were taken, or in the windows of other cars, either new or old, depending upon conditions and circumstances.

What I claim as my invention is:

1. In car window sash construction, the combination of hollow sheet metal sections salvaged from old sashes bevelled at their ends to form a miter-joint for the corner of the sash, having slots (20 and 21) there-in, and also openings (22 and 23) for screws, a sheet metal corner splicer (17) enclosed in the sash to hold the two sections together at said corner, having a reinforce (18) for said corner splicer, secured there-to by rivets (19) inserted through the splicer and said reinforce, a lock provided with lugs (29 and 30) for insertion in said slots, said splicer having openings (24 and 25) for screws, and said lugs having openings (31 and 32), the openings (22, 24 and 31) being in alinement to receive a fastening screw when the various elements are assembled, and the openings (23, 25 and 32) being in alinement to receive another screw, 95 whereby said screws secure the lock and splicer together.

2. In car window sash construction, the combination of two hollow sheet metal sections salvaged from old sashes having their 105 ends brought together to form a butt-joint between the corners of the sash, and a splicer comprising parallel side members (13) spaced apart by rivets (14) to fit the interior of the sections and reinforce the butt-joint, said splicer being sweated in place, 110 substantially as described.

Signed by me at Chicago, Ill., this 5th day of April, 1918.

CHRISTIAN N. ILSENG,
